(57) **CLAIM**

The ornamental design for a vehicle scanner, as shown and described.

DESCRIPTION

FIG. 1 is a top plan view of a first embodiment of the vehicle scanner;

FIG. 2 is a left side perspective view of the FIG. 1 embodiment;

FIG. 3 is a left side elevation view of the FIG. 1 embodiment;

FIG. 4 is a front side elevation view of the FIG. 1 embodiment;

FIG. 5 is a top perspective view of the FIG. 1 embodiment;

FIG. 6 is a second left side perspective view of the FIG. 1 embodiment;

FIG. 7 is a left side plan view of the FIG. 1 embodiment;

FIG. 8 is a rear perspective view of the FIG. 1 embodiment;

FIG. 9 is a second left side perspective view of the FIG. 1 embodiment;

FIG. 10 is a third left side perspective view of the FIG. 1 embodiment; and,

FIG. 11 is a right side perspective view of the FIG. 1 embodiment.

Broken lining shows features of the vehicle scanner that are not considered to be part of the design.
